UNITED STATES PATENT OFFICE.

GEORGE B. EDDY, OF CAMDEN, NEW JERSEY.

VALVE-GEAR FOR LOCOMOTIVE-ENGINES.

SPECIFICATION forming part of Letters Patent No. 657,816, dated September 11, 1900.

Application filed April 28, 1900. Serial No. 14,714. (No model.)

To all whom it may concern:

Be it known that I, GEORGE B. EDDY, a citizen of the United States, and a resident of Camden, in the county of Camden and State 5 of New Jersey, have invented a new and Improved Locomotive-Engine, of which the following is a full, clear, and exact description.

The object of the invention is to provide a new and improved locomotive-engine arranged to provide at all times a full exhaust no matter what position of cut-off the admission valves are in at the time, thus relieving the engine of all back pressure and at the same time allowing the motive agent to work 15 expansively in the usual manner.

The invention consists of novel features and parts and combinations of the same, as will be fully described hereinafter and then pointed out in the claims.

20 A practical embodiment of the invention is represented in the accompanying drawings, forming a part of this specification, in which similar characters of reference indicate corresponding parts in both the views.

25 Figure 1 is a sectional side elevation of the improvement as applied, and Fig. 2 is an enlarged transverse section of the same on the line 2 2 in Fig. 1.

The engine-cylinder A, in which reciprocates the piston A', is connected by ports a b with the interior of a steam-chest B, containing a valve-seat C for an exhaust slide-valve D, having the usual cavity c, and operating over branch ports a' b' to insure full exhaust 35 of the steam from the cylinder to the exhaust-outlet E no matter what position of cut-off the admission-valves G G' are in at the time. The admission-valves G G' are mounted to slide in unison on extension valve-seats F F', 40 respectively, through which extend the ports a b, as is plainly indicated in Fig. 1, and said admission-valves are coupled together by a valve-rod H, pivotally connected at I to the arm J of a rock-shaft K, connected by

45 an arm T with a link-block S in a link U, controlled in the usual manner by the engineer, and connected with the eccentric-rods V V' of eccentric-straps W W', engaging eccentricities X X' for imparting the usual motion to 50 the link, so as to move the admission-valves G G' on their valve-seats F F'. By the engineer raising or lowering the link U rela-

tively to the block S a greater or less movement is given to the arm T and a corresponding movement to the admission-valves 55 G G' to control the cut-off of the steam from the steam-chest B to the ports a b.

The exhaust-valve D is connected by a valve-rod N to an arm O, secured on an auxiliary rock-shaft P, carrying a depending arm 60 Q, provided with pins R R', projecting from opposite faces of the arm, as indicated in Fig. 2. The pins R R' are adapted to be engaged by U-shaped hooks Y Y', respectively, formed on the eccentric-rods V V', so that the particular hook engaging the pin R or R' imparts to the arm Q the full movement of the eccentric-rod regardless of the exhaust position of the hook relatively to the pin. For instance, when the hook Y is in engagement with the 70 pin R it will be seen that the movement brought about by the eccentric X will be transmitted to the exhaust-valve D, and this movement will be substantially the same whether the link U is raised or lowered to a certain 75 limit, so long as the hook is in engagement with its pin, thereby permitting the varying of the throw of the admission-valves by the change of position of the link U relatively to the block S without, however, changing the 80 throw of the exhaust-valve D. When the engineer reverses the engine by lifting the link U, then the hook Y moves out of engagement with the pin R, and the hook Y' moves in engagement with the other pin R', so that the 85 movement of the eccentric-rod V' is transmitted by the hook Y' to the pin R' and the arm Q to rock the shaft P and to impart a sliding motion to the exhaust-valve D, the same as above described relatively to the 90 hook Y engaging the pin R—that is, the exhaust-valve D receives a full stroke no matter what position of cut-off the link U is in or whether said link is in a lowermost or uppermost position for running the engine forward or backward.

From the foregoing it will be seen that steam will be admitted to the cylinder through the ports a b, and this admission of steam will be entirely controlled by the valves G G', 100 while the dead steam will be exhausted through the branch ports a' b' and the exhaust-valve D, so that the admission and exhaust are independent of each other. It will

further be seen that the throw of the exhaust-valve D remains fixed, while that of the admission-valves G G' is under the control of the engineer, so that the stroke may be varied 5 for varying the point of cut-off for running the engine forward or backward.

By the arrangement described the admission-valves G G' allow full admission of the steam to the cylinder, so that in starting or 10 when doing heavy work the piston is acted upon by a full admission of steam. As the exhaust-valve has a full throw at all times there is no back pressure liable to occur in the cylinder, and at the same time the steam 15 is free to expand in the cylinder, as the exhaust does not take place until the piston nears the end of its stroke.

The device is very simple and durable in construction and is not liable to get out of 20 order, costs little for repairs, and insures better and easier running of the locomotive and without any jerking motion.

Having thus fully described my invention, I claim as new and desire to secure by Letters 25 Patent—

1. An engine having admission and exhaust valves having independent motion, the stroke of the exhaust-valve being fixed and that of the admission-valve variable, an eccentric 30 mechanism, a link-motion actuated by said eccentric mechanism and controlling said admission-valve, and mechanism for operating the exhaust-valve from the eccentric mechanism to impart a full stroke to the exhaust- 35 valve irrespective of the position of the said eccentric mechanism.

2. In an engine, the combination with admission and exhaust valves, eccentric rods carrying a link, and means for operating the 40 admission-valves from the said link, of an exhaust-valve-operating mechanism, and means for operating the said mechanism from the eccentric-rods to impart a full stroke to

the exhaust-valve irrespective of the position of said link, substantially as described. 45

3. In an engine, the combination with admission and exhaust valves, eccentrics, eccentric-rods carrying a link, and means for operating the admission-valves from the said link, of a rock-shaft provided with oppositely-projecting arms, with one of which the eccentric rods are adapted to be alternately engaged, the other arm of the said shaft being connected with the exhaust-valve rod, substantially as described. 50 55

4. In combination with valves of the character described, a valve mechanism consisting of two eccentrics, eccentric-rods connected thereto by straps, a link to which said eccentric-rods are attached, a block which said link embraces, an arm carrying the block, a rock-shaft to which said arm is secured, another arm carried by said rock-shaft, whereby motion is transmitted to the admission-valves, a second rock-shaft, an arm projecting downward therefrom, pins projecting from said arm, hooks carried by the eccentric-rods for engaging said pins, and means for transmitting the motion of the hooks to the exhaust-valve, as specified. 60 65 70

5. A valve mechanism consisting of two eccentrics, eccentric-rods connected thereto by straps, a link to which said rods are pivoted, said link operating upon a block, for transmitting a variable motion to the admission- 75 valves, hooks carried by the eccentric-rods, and means for transmitting a given motion from either eccentric from the hooks to the exhaust-valve, substantially as described.

In testimony whereof I have signed my name to this specification in the presence of two subscribing witnesses.

GEORGE B. EDDY.
